HAND TOOL

Filed Aug. 30, 1929

INVENTOR:

R. W. HURD

By George F. Wright,
ATTY.

UNITED STATES PATENT OFFICE

RALPH W. HURD, OF OAKLAND, CALIFORNIA

HAND TOOL

Application filed August 30, 1929. Serial No. 389,462.

My invention relates to improvements in a hand tool operable in conjunction with a safety razor blade, which may be a discarded blade, and it is particularly adapted for use 5 as a scraper for cleaning window panes and the like, although also useful as a ripping tool for cutting the basting threads and the like of garments, etc., but also useful for other purposes; and one of the objects of 10 the improvements is the provision of a hand tool of this character that is compact, efficient, and inexpensive to manufacture; a further object is the provision of means on the tool adapted to protect the cutting edge 15 of the blade when it is not in use, as when the tool is deposited in a tool-box or the like, as well as to protect an operator from being accidentally cut by the blade when carrying it on his person as when it is deposited in 20 a pocket of his garments or the like.

With the foregoing and still further objects and purposes in view which will appear as the description proceeds, my invention resides in the combination and arrangement of parts and in the details of construction hereinafter described and claimed, it being understood that changes in precise embodiment of the invention herein disclosed can be made within the scope of what is 30 claimed without departing from the spirit of the invention.

In the accompanying drawings—

Figure 1 is a plan view of the tool ready for use;

Figure 2 is the tool with the top plate removed;

Figure 3 is a view similar to the last preceding figure, but with the razor blade removed.

Figure 4 is a plan view of the top plate;

Figure 5 is a plan view showing the top plate moved forward to protect the exposed edge of the blade;

Figure 6 shows the top plate moved further forward into a position for disassembling the device;

Figure 7 is a median longitudinal sectional view on line 7', 7' of Fig. 1;

Figure 8 is a like sectional view on line 50 8', 8' of Fig. 5;

Figure 9 are longitudinal sectional views of the several elements comprising the tool, disassembled;

Fig. 10 is a cross section on line 10', 10' of Fig. 1;

Fig. 11 is a cross sectional view on line 11', 11', Fig. 1;

Figure 12 is a view in cross section on line 12', 12' of Fig. 1;

Figure 13 is a sectional view on line 13', 13' of Fig. 3;

Figure 14 is a view on line 14', 14' of Fig. 4; and

Figure 15 is a longitudinal sectional view on line 15', 15' of Fig. 4.

The drawings represented by the Figures 10 to 15, inclusive, are of a relative larger scale than the drawings of the preceding figures.

Referring to the drawings in detail, throughout which like reference characters designate like parts:

The numerals 1, 2 and 3, designate the top plate, bottom plate, and the razor blade, respectively, of the present hand tool.

The plates 1 and 2, which are formed of sheet metal, preferably of soft spring-steel to provide the proper degree of resiliency, and which plates coact for holding the blade 3 operatively therebetween, are bowed longitudinally outwardly as best shown in Fig.

9, and have front edges 4 and 5 substantially at right angles with the axes of the plates, and rear edges 6 and 7, the latter preferably rounded in the plane of the plates that they may be the better gripped by the hand of the operator.

On the inner side of the top plate 1, adjacent its opposed ends 4 and 6, are formed oblong indentations 8 and 9, of which the indentations 8 register with the openings 10 in the blade 3. In striking the indentations 8 and 9, there are formed on the opposite side of the plate oblong elevations 8' and 9' extending longitudinally of the plate.

Intermediate the elevations 8', 9', is formed a comparatively broad slot 11, the rearwardly end of which is enlarged laterally, to provide side extensions 12, while the side edges of its forward portion are pro-

100

vided with upwardly extending, rearwardly tapering, wedge-shaped binding shoes 13, the latter terminating preferably short of the extensions 12.

5 Upon the inner side of the bottom plate 2 are formed conical bosses 14, 15, of which the former register with, and project through, the openings 10 in the blade 3.

10 Out of the mid body portion of the plate 2, intermediate the bosses 14, 15, are struck a pair of spaced uprights 16, which terminate at their free ends in opposed outwardly projecting locking lips 17, the lower ends of the uprights 16 being left integral with the body of the plate.

15 The blade 3, through the openings 10 of which the bosses 14 project, is normally stationary relative to the plate 2, but may be removed therefrom by lifting it off the bosses 20 when it is desired to reverse it or to replace it with another blade. The blade shown in the present form of the device, is of the Gillette or double-edge type. Other types or forms of blades having the required openings, may be used if desired.

25 The plates 1 and 2 are preferably substantially of equal lateral and longitudinal dimensions with boundaries registering when disposed in normal or operative position, which is best shown in Fig. 1, and in which position the bosses 14 are disposed to project through the openings in the blade 3 into the forward end portion of the indentations 8, and boss 15 disposed to project into 30 the forward end portion of the indentation 9, and the uprights 16 projecting through the forwardly end portion of the slot 11 with the locking lips 17 bearing on the forwardly end portions of the binding 35 shoes 13. The plates 1 and 2 are bowed outwardly in opposite directions longitudinally when disassembled (see Fig. 9) and spring-press against the blade from opposite sides when assembled and locked in operative position (see Fig. 1) by means of the locking 40 lips 17 projecting through the slot 11 and bearing against the shoes 13.

45 When the tool is not in use and it is desired to protect the blade from injury, or 50 from doing injury by accidentally cutting an object as when carried in the pocket or the like, the top plate 1 is moved forwardly relative to the bottom plate 2 and the blade 3, into the position shown in Fig. 5. In this 55 position, it will be noted, the lips 17 are disposed intermediate the shoes 13 and the slot extensions 12, the bosses 14 moved to the rear end portions of the indentations 8 and the boss 15 moved to the rear end portion 60 of the indentations 9. And when it is desired to disassemble the device, as for the replacement of a blade or the like, the top plate 1 is moved still further forward relative to the bottom plate and blade, until 65 the bosses 14 and 15 are forced beyond their

respective indentation in the top plate, and the lips 17 register with the extensions 12 (see Fig. 6) when the spring-tension of the plates forces their mid portions to move apart bodily and the lips to slip through the extensions 12. The plates are now unlocked and the top removable by lifting it up. To assemble the plates and blade, the modus operandi just described for disassembling them is reversed.

70 18 designates a knurled area on the top plate intermediate the slot 11 and elevation 9', which knurling is formed either by indenting or by cutting into the surface of the outer side of the plate to roughen it to 75 provide better frictional effect when gripping it by the thumb or fingers of the hand for operatively moving one of the plates relative to the other. This knurling of the top plates, while not shown in Figs. 5 and 6, and 80 not shown at all in the bottom plates, is intended to be carried out in both places.

85 It is to be noted that while the forwardly left-hand corner of the plate 1 is rounded, the right-hand corner is substantially rectangular. This is done to provide a comparatively angular projection at said right-hand corner useful for probing and scraping in the valleys and corners of window sash and the like when the tool is employed 90 for cleaning same.

95 What is claimed is:

1. In a hand tool of the character described embodying a pair of plates adapted to cooperate for holding a razor blade between registering ends thereof, of a plurality of oblong indentations disposed in spaced parallelism on the inner side of one of said plates and extending longitudinally thereof, said indentations being concavo-convex in 100 cross section and forming oblong elevations on the opposite side of said plate, a plurality of conical projections on the inner side of the other of said plates disposed to operatively slide in said indentations, and means 105 on one of said plates projecting through a mid portion of said other plate and bearing thereagainst for movably binding said plates together.

110 2. In a hand tool of the character described embodying a pair of plates adapted to cooperate for removably holding a razor blade therebetween, of three oblong depressions formed in the inner surface of the forward end portion of one of said plates, said depressions disposed in lateral spaced relation and extending longitudinally of 115 said plate, an oblong depression formed in the surface of the inner side of the rear end portion of said plate, said depressions being concavo-convex in cross section and forming oblong elevations on the opposite side of said plate, a plurality of conical projections on the inner side of the other of said plates disposed to operatively slide longi- 120 125 130

tudinally along in said depressions, and means in the mid part of one of said plates projecting through an opening in the other plate and bearing against the outer side of the latter, said means adapted for relatively movably binding said plates removably together.

3. In a hand tool of the character described, of a plate having an oblong depression formed in the inner side of its forward end portion, an oblong depression formed in the inner side of the rear end portion of said plate, said depressions being concavo-convex in cross section and forming elevations on the outer side of the plate, said plate having a slot intermediate said depressions, said depressions and slot being disposed in general axial alignment, and a wedge-shaped binding shoe on opposite sides of said slot.

4. In a hand tool of the character described, of a plate having a slot in its mid part having a wedge-shaped binding shoe on opposite margins, and a plate having a pair of laterally spaced uprights projecting through said slot, said uprights terminating at their free ends in opposed locking lips adapted to slidably bear against said binding shoes for movably binding said plates together.

In testimony of the foregoing being my own, I have hereunto affixed my signature this 22nd day of August, 1929.

RALPH W. HURD.
